UNITED STATES PATENT OFFICE.

JACOB E. BLOOM, OF BROOKLYN, NEW YORK.

PROCESS AND APPARATUS FOR THE ELECTRICAL TREATMENT IN THE DYEING OF FIBERS AND FIBER PRODUCTS, AND THE DYESTUFFS AND THE PRODUCT RESULTING THEREFROM.

1,333,700.

Specification of Letters Patent. Patented Mar. 16, 1920.

Application filed December 3, 1917. Serial No. 205,228.

To all whom it may concern:

Be it known that I, JACOB E. BLOOM, a citizen of the United States, residing at Brooklyn, city of New York, in the county 5 of Kings and State of New York, have invented certain new and useful improvements in processes and apparatus for the electrical treatment in the dyeing of fibers and fiber products, and the dyestuffs and 10 the products resulting therefrom, of which the following is a specification.

This invention relates to an electrical treatment in the dyeing of fibers and of manufactures of fibers and dyestuffs and 15 what are known as loose compounds used in dyeing, and to the apparatus therefor, and to the products thereof; and is illustrated herein particularly in the dyeing of textile fibers, or cloth or the like.

20 Among its objects are that of more uniformly and permanently fastening or fixing dyestuffs and more particularly sun-dry dispersoids and adsorbable suspensoid and irreversible colloidal substances 25 from solution, or disperse medium, and ensuing reaction products, upon the fiber as the adsorbent, in stable condition, by electrical transference and adsorption, by means of treatment in or passage through 30 fields of alternating electric, magnetic or electro-static stresses or fields, advantageously created by symmetrical alternating currents, advantageously of low frequency. A material saving and economy in liquors 35 in many cases, is also attained by my process.

In this application, I apply and illustrate more especially the process and apparatus with alternating fields between electrode terminals, with the fibrous adsorbent passing therebetween advantageously with means to apply first one single phase A. C. field during the passage of low frequency and following immediately with the alternative use thereafter of two or more opposing or conflicting fields from a polyphase system or with opposing alternations, simultaneously or synchronously created in the liquid from other A. C. source of practically equal but opposite sine value, of equal amperage, advantageously of equal medium to high frequency; such latter alternations from opposing or conflicting circuits meeting hammer-like approximately

upon the interpolated cloth as adsorbent, under insulated conditions; and with resulting increased density of the combined dyestuffs, upon the fiber.

Other objects are set forth in the body of the specifications and claims.

As a process, my invention comprises a process of first advantageously dispersing in a suitable medium or making a solution as at present of the dyestuffs to be used, advantageously treating same to attain dispersoid state in an A. C. field; and then treating the fiber or cloth or fibrous material under insulated conditions preferably in dielectric or insulated vessels, in suitable liquids or colloidal solutions or dispersoids dispersed in suitable mobile media, such as the dye-liquors now utilized in the art of dyeing textile cloth, by subjecting the same while duly immersed in the liquid at suitable temperature, to the influence of alternating electric stresses or fields between electrodes in the solution; or to the influence of induced electric or magnetic or electrostatic stress or stresses or fields, in the solution, from exteriorly generated alternating current source, advantageously first from a single phase system, advantageously of low frequency, and in some cases followed by polyphase system of medium or high frequency;—the latter A. C. currents being arranged in circuits so as to create in the liquid, opposing or conflicting alternating electric fields of alternations of like frequency and advantageously of like amplitude, voltage and amperage, and advantageously symmetrical, and of flattened top wave form; and the material and liquids being under control as to temperature and movement or agitation; the circuits from such multiple alternating currents being arranged to act, hammer-and-anvil-like, in the liquid both upon the soluble dispersoid substances in the liquor, as also upon the solid adsorbent, immersed in the liquid, to-wit: a textile fiber or cloth and the like, intended to be treated, i. e. dyed by the dyestuffs, in said liquid; simultaneously the liquid is advantageously passed intermittently or continuously with suitable pressure through or into contact with the cloth, which is being passed therethrough by suitable means; or the fibers in loose condition being agitated therewith, under

regulated periods of time, and temperature, a greater or less period of time, at higher or lower temperature, such being varied for the differening dye colorings or ends to be attained.

Alternatively, the textile cloth or hank or warp may be passed through the liquid intermittently, or continuously, under regulated temperature and time and speed of passage.

Alternatively, only a single A. C. stress is to be first applied, of low frequency, to better insure the adsorption of the dye-stuff from solution to and upon the fiber; and thereafter in some cases follow the operation by applying the opposing A. C. stresses of the polyphase system of higher frequency aforesaid.

In some cases the solution, if not so naturally, is advantageously first made slightly acid by the addition of suitable acids; and thereby, the fiber becomes positive by immersion; and the above electrical treatment is then applied, resulting in the fixed adsorption of the suspensoid or dispersoid negative particles from solution; and thereafter in some cases, a solution is prepared to be basic or alkaline by the addition of suitable salts or alkalis; and in which the fiber may become negative by immersion; and then the electrical treatment is again applied resulting in the adsorption of positive particles, or of emulsoids previously rendered positive by above first treatment, and fixed on the fiber in the second treatment, generally by combining and compounding with other dispersoids or colloids or ions or colloidal and chemical compounds on the fiber; if the emulsoids or amphoteric substances are not thereby fixed, such are electrically repelled and continue in solution. In some cases, the foregoing treatments are reversed, *i. e.*, said second treatment is first used. In other cases, such latter or the preceding treatment only is used. The operation is advantageously conducted under insulated conditions, during the periods of time when the currents are applied; or the liquors when the single phase A. C. field is alone applied, then advantageously having intermittent earth or discharge connection through an insulated grounding wire having an exterior interrupter passing or transmitting to earth only free positive charges and leaving a negative charge upon particles in the liquid or the adsorbent; or vice versa; the process in either case being conducted advantageously until the suspensoid colloids and adsorbable dispersoid particles have been firmly electrically adsorbed from the solution by the fiber and firmly compacted or fixed thereon; and until emulsoids which have not become fixed and continue reversible or reversible particles and gases and vapors and other soluble impurities have

been forced or compressed out of the fibers thereby, *i. e.*, by the alternating forces of the A. C. fields.

Alternatively and furthermore such treatment may in some cases be applied advantageously both before and during the dyeing process proper, *i. e.* first: apply the electric stresses before immersing the fibers in the liquor, in order to prepare the liquor advantageously for the process, by thereby and therein attaining homogeneous electrical adsorptions and fixedness with less sensitivity in the dye-liquor and dye-stuff and perfecting the dispersion of the dispersoids and adsorbable colloids; and secondly, then applying the electric fields during the immersion or passage of the fiber in or through the dye liquor, *i. e.*, dyeing process proper, in order to continue said first advantage; and further in order to cause further and firmer adsorption and fixation on the wet surface of the fiber or the dispersoids or adsorbable dyestuff from the solution in a homogeneous and fixed manner.

The first treatment of the liquor alone may be in some cases dispensed with, and the latter treatment with the fiber only used.

It will be understood that this process may be repeated several times if desired, or in several successive vessels, depending upon the depth of color or other effects desired to be obtained.

As an apparatus, my invention comprises a vessel or vat or chamber thereof, advantageously constructed or lined with glazed porcelain or stoneware or glass or other dielectric, and acid or alkali resisting material, the whole supported on insulating material, together with means for supplying to, circulating in, and removing from said vat, a suitable dye-stuff solution or liquor, *i. e.*, having a suitable stuff or element in solution, or in disperse state herein, with particles advantageously adsorbable and colloidal or dispersed in suitable mobile medium; and having means for controlling the temperature of the liquor advantageously to about 130° F. and in some cases to about 30° F., where the solution or disperse liquid remains liquid at such temperature and in some cases with means for the agitation or movement thereof or passage thereof through the vessel, and to make contact with the textile fibers therein; and with means for supplying to, immersing in and removing from said vat and liquor therein, the loose fibers or cloth or continuous paper and the like, advantageously between A. C. electrodes; or means for passing textile cloths or "hand" or "warp" continuously or intermittently into and through said vat and liquor; and means for effecting such passage advantageously between suitable A. C. electrode plates, of material neutral and insoluble, and advantageously hollow, and in some cases the elec-

trodes carrying a cooling solution insulated therein; means for controlling the period of time of such immersion and passage, and an intermittently insulated condition thereof; 5 means for producing and maintaining in said vat and for subjecting said liquor and the immersed textiles, fibers, etc., while moving therein to the influence of stresses in alternating electric field or fields from externally generated alternating current source, 10 first from single phase low frequency and followed in some cases by polyphase system of medium or high frequency, advantageously symmetrical and of like frequency 15 advantageously of like amplitude and flat top wave, and voltage and amperage, with the latter circuits arranged to create in the liquid and upon the fiber conflicting or opposing alternations of equal magnitude 20 either in induced A. C. fields or between sets of suitable insoluble inert electrode terminals, of large and equal area, immersed in the solution, advantageously close together and with the fiber there-between; and means 25 for controlling said A. C. fields; means for keeping the liquid and the apparatus under insulated conditions; means for electrically connecting to earth the liquor or solution in said vat, when said A. C. stresses are applied, through an electrode-like plate or wire 30 in the liquid, called a leader plate, connected to an insulated wire leading to earth, through an insulated interrupter, adjustable to allow only positive or only negative alternations 35 to pass to earth, (and advantageously in synchronism with the frequency of the above A. C.); or through an electrolytic rectifier or like device permitting positive charges only to be grounded automatically, or the 40 reverse.

In one form, I advantageously provide separate circuits for each of two-phase currents differing in phase angle by about 180 degrees so as to set up opposing or conflicting alternations in the liquid; and by providing separate terminals or sets of insoluble inert electrodes having advantageously equal surface area, in the vessel for each circuit; and I prefer to arrange such electrodes 45 by placing the anode of one circuit to face and oppose as nearly and closely as practicable, the anode of another circuit; and cathode electrodes ditto; and thereby so arranged, that practically the circuits or alternations in the liquid flow in conflict or in opposition,—*i. e.*, the positive (or negative) alternation of one circuit being practically counteracted by the simultaneous equal and positive (or negative) alternations respectively of the other circuit and which alternations practically meet upon or act hammer-like or conflict upon the fiber or other adsorbent interposed between the like electrodes of the several circuits in the liquid. 55

60 65 Thereby in addition to the mere adsorp-

tion, there is attained a hammer-like or compacting effect upon and within the fiber, which aids in the "fixing" and increase of density of molecular compounds, and of absorptions, and in the "compacting" of the 70 substances of the fibers or other adsorbent and in the driving out from the interstices of the fibers any free acids or vapors and impurities solvent in the liquid and the free emulsoids and the like. 75

The said action and effect is influenced and affected also by the lag of the current behind the voltage and which may be enhanced by placing an inductance in one lead of each of said A. C.'s. 80

It is advantageous to provide in the A. C. circuits a condition of resonance, and that the circuits each contain inductance, resistance and capacity, in series. 85

An ammeter and rheostat, not shown, are placed in each A. C. circuit, excepting as shown by resistance r and r' in circuits Fig. 8. 90

In some cases, I facilitate the earthing of the freed positive or negative pulsations or charges when quite faint after passage through the interrupter, by passing same through a Ruhmkorff coil or a closed core transformer or the like, to obtain increased voltage to earth. 95

As a product, my invention comprises dyed fiber manufactures such as a dyed textile cloth or the like, and electrical-adsorption compounds such as the dyestuffs used in the dyeing, having and comprising electrically adsorbed thereon or therein, from suitable liquids, sundry dispersed particles and suspensoid colloids and irreversible particles and mutual precipitations, and reaction compounds, with or without chemical reaction compounds of said adsorptions with each other, or with the colloidal substances or components of the fiber, or with other adsorbents; such adsorptions and reactions being formed and fixed and compacted by 100 electrical transference and electrical adsorption and compression in addition to natural adsorption; and all attained homogeneously and in non-strained equilibrium, resulting in enhanced fixed and stable state or conditions, and with increased true density or specific gravity of adsorbed molecules or dyestuffs. 105 110 115

Again, one form of my product may be described, as a chemically sensitive dyestuff substance, or a fiber dyed therewith which dyestuff is ordinarily of loose molecular structure and strained equilibrium, as regards the dyestuff, but is electrically transformed by the process to a substance of same 120 molecular group or groups but of less sensitivity, and of firm stable fixed and durable molecular structure, and in non-strained equilibrium. 125

Extremely sensitive substances, such as 130

the diazo compounds or dyestuffs, nitrogen halids, and the like, are difficult to manipulate on account of extreme sensitiveness; and it is believed such and other extremely sensitive substances are especially of loose molecular structure and in strained equilibrium.

My process in many cases, fixes and stabilizes this "loose molecular structure," and 10 effects a transition to and attains firm fixed and more stable molecular structures in non-strained equilibrium, through the electrical adsorption force added to the natural adsorptions, of non-amphoteric colloids and 15 disperse particles, and amplified or enhanced by the compacting or compressions upon such natural adsorption structures, and simultaneously driving out the amphoteric colloids and particles and gases.

20 This view and effect of my process pertains advantageously to sundry molecular groups, or structures of sundry atomic groups, of dyestuffs and the like now characterized by the more or less ease with which 25 they break down, to wit:

$\text{N}=\text{N}$, in diazo compounds, in hydronitric acid and in others; example $\text{C}_6\text{H}_5\text{N}=\text{NO}_2$, diazobenzenenitrate.

$\text{N}-\text{C}$, in the fulminates, in cyanogen 30 C_2N_2 and others.

$\text{N}=\text{O}$, in inorganic and organic nitrates, in nitro bodies and others; example $\text{C}_2\text{H}_5\text{ON}-\text{O}$, ethyl nitrite.

$\text{N}-\text{Cl}$, in NCl_3 , nitrogen trichlorid.

35 $\text{C}-\text{C}$, in acetylene C_2H_2 , and in the poly-acetylenes.

$\text{O}-\text{Cl}$, in chlorates, perchlorates and others; example $\text{CH}_3\text{O}-\text{Cl}$, methyl hypochlorite.

40 $\text{O}-\text{O}$, in ozone, in peroxid and others; example $\text{C}_2\text{H}_5\text{OO}-\text{OC}_2\text{H}_5\text{O}$, acetyl peroxid.

It will be noted, that by my electric process, and with the ground connection to carry to earth only the surplus freed positive 45 charges; I attain electro-negative groups in solution, or in disperse state, which effect adsorption electrically fastened associations or adsorption compounds, of enhanced stability, in or with the solvents, and which 50 continue of enhanced stability after the solvents are removed, to wit water, the alcohols, phenols, carboxylic acids, amids and anilids,—oxims,—nitriles,—mercaptans,—thio-acids and amids,—primary amines,—nitroso compounds,—aldehydes and ketones; and said electro-negative groups include:

OH , — COOH , — CONH , — NOH , — CN , — SN , — CSNH , — CSOH , — NH_2 , — NO , — CNO , — CO , — CS .

60 Such pertains not only to sundry organic adsorption compounds thereby electrically fixed, but likewise with sundry inorganic compounds including the oxids, to-wit the nitrogen peroxid,—phosphorus oxid in benzene,—arsenious oxid in nitrobenzene,—hy-

drogen chlorid,—nitric acid. It is to be noted that the mere presence of nitrogen or trivalent nitrogen, or of elements like chlorin, bromin and iodin, oxygen and sulfur, does not bring about these adsorption 70 dyestuff compounds or associations,—but such are formed when the element is present in one of the electro-negative groups indicated. I advantageously attain such electro-negative groups with my process using 75 an interrupter passing to earth only surplus positive charges.

It is not essential that either or all the constituents of an adsorption compound shall be what is ordinarily known as "associated"; 80 many such are formed from unassociated constituents; among such organic substances are the compounds of naphthalene, phenanthrene and fluorin with di- and trinitrobenzenes and tri-nitrotoluene, etc. 85

It is advantageous to keep the solution at low temperature, as high temperature tends to cause dissociation,—during the processing and thereafter.

In the operation of my process, in some 90 cases where it is doubtful or impractical to determine in advance or theoretically whether to use an interrupter to pass to earth the positive or negative free or unbalanced charge, then it is advisable to test the 95 product when the negative charges are retained, and again when the positive charges or pulsations are retained; the superiority of the one product over the other as regards stability or density or other test will definitely 100 fix the preferable adjustment or kind of interrupter to use, in making the particular product. And likewise as regards the use of an impedance coil in one lead of one A. C. circuit when the interrupter is placed in the 105 other lead of same circuit. And likewise as to whether before the use of the dyestuff in solution or in disperse state to first make it acid or alkaline or neutral. And likewise as to the placing or not of an inductive 110 resistance in series in each of the A. C. circuits.

It has been noted that when a solution of sodium nitrite is added to a solution of a primary amine (containing the group $\text{N}.\text{H}_2$), and the mixture is acidified, diazo compounds, containing the group, $-\text{N}=\text{N}-$, are formed which are usually unstable and sometimes explosive, but nevertheless give rise to a large number of valuable dyes. 115

The azo dyes form the largest group of dyes known.

In the past or existing method of preparing azo dyes the operating in general is as follows: (1) "A molecular proportion of the 125 amine to be diazotized, is dissolved in water, with about $2\frac{1}{2}$ molecular parts of HCl acid; a solution of a molecular part, of nitrate, is then run in gradually, while the reaction mixture is kept cool and stirred. (2) After 130

diazotization is complete, the solution is added to a solution of a molecular proportion of a second component, and stirring is continued until the combination is finished; 5 the dye either precipitates or is salted out by means of salt or hydrochloric acid, and is filtered off, washed and dried."

My improved process is applied (1) after the said first reaction mixture becomes cool 10 or quiescent; and (2) again after the diazotization and during the mixing or blending with the second component until the electric adsorption in lieu of the ordinary combination, is effected and completed; (3) the dyes 15 and the like are caused to crystallize or precipitate from solution in smaller particles and large crystals avoided through the application of the A. C. field advantageously of low voltage and with low temperature attained by due cooling means; and, (4) likewise in any subsequent dyeing therewith in solution; or subsequent admixture thereof in solution.

The said nitrogen compounds are adsorbable; and therefore advantageously adsorbed in said operations in the A. C. fields.

Thereby I attain homogeneous dyes and dyeing and with enhanced density or specific gravity, and increased stability.

30 By the term "suitable" as used herein as applied to the liquid or solution, *i. e.* the suitable dye-liquor, I mean a duly prepared solution containing the dyes, etc., substantially as at present or with improvements, 35 and comprising dispersoids in disperse state, adsorbable colloids and adsorbable constituents; but with the addition thereto, in some cases of suitable acids, acetic, sulfuric or tauric, etc.; or in other cases the addition of 40 alkalis, sodium carbonate, sodium acetate or soap, etc.; or in other cases the addition of neutral salts, *i. e.* sodium sulfate or common salt, etc.; and whereupon the above process is applied, to give to a component or ion or 45 to the fibers when immersed in the solution, in the alternating current field the electric sign desired, *i. e.* opposite to that of the particular dispersoid or colloid or solute or particle, *i. e.* dyestuff, etc., to be adsorbed and 50 taken out of solution or fixed upon the fiber, under the influence of the active difference of potential created when the said alternating current fields are applied; and thereby the fiber becomes selective for the particular 55 dyes or effects desired.

Where a neutral or alkaline liquor is used, as with the direct cotton dyes, it is necessary to soften hard water before use, as by boiling the water with a small amount of soda ash.

60 By the term "adsorbent," I include not only primarily a fiber, or other solid adsorption material, immersed in the solution, but also a dispersoid or a colloid, in thin disperse state in the liquid mobile medium, or sundry 65 ions, or other particles, and any of which

adsorb other dispersoids or colloids by the electrical charging and transference, and adsorption of the latter upon the former, in an alternating electric field.

By the term "electrically hammered" or "compacted" I mean where the fiber has adsorbed any dispersoids or colloids, or where any other adsorption upon the fiber or dispersoid or colloid has taken place in and from the solution, which is being treated in the single phase alternating electric field; the subsequent alternations of the polyphase system fields, act hammer-like, simultaneously conflicting upon or in the fibers, or composite or chemical molecule mixture and blend, and thereby further physically compacts, increasing the density of the molecule and strengthens the adsorption bond, so that the adsorption compound thereafter is more firmly fixed and fastened, and is not what is commonly known as a loose compound.

By the term "electrical homogeneity," or "electrically homogeneous adsorption" and the like, I mean where there has been an electrical adsorption in the said alternating current fields, as in the dye liquors whereof the dispersoids and sols are electrically adsorbable instantaneously by other dispersoids or colloids throughout the solution etc., or by and in the fiber; and thereby homogeneity is attained in the composite solution or dye-liquor, and later in the adsorptions upon the fiber and the like.

I do not restrict this invention to the particular specific illustrations cited, but use same in other somewhat analogous types as for instance, in impregnating a fabric or paper with pigments or to make same fire-proof or rot-proof or water-proof or in treating leather or hides, or making artificial leather, or in lacquering or in making or treating photo films or the like, especially with pyroxylin or cellulose acetate or cellulose nitrate solutions.

The invention as thus outlined will be 110 hereinafter more fully set forth, more particularly as illustrated by dyeing, and dyestuffs. It is understood there are a large number of dyestuffs and sundry existing methods of dyeing the different kinds of 115 fibers, both at high and low temperatures, and which methods may be and are largely to be used with the addition of the present invention.

I attain my invention by the novel apparatus illustrated in the accompanying drawings, in which similar letters and numbers refer to similar parts; but it will be understood I do not restrict myself to the particular apparatus shown.

Figure 1 is a vertical longitudinal section of a vat in diagram, in part embodying the apparatus of the invention for treating a fibrous material when in the form of a cloth to be treated, *i. e.* dyed, with means

for drawing the cloth over roller guides and between A. C. electrodes being the terminals of alternating electric fields, in suitable dye-liquors.

5 Fig. 2 is a vertical cross section on line y y' of Fig. 1.

Fig. 3 is a vertical section of another vat, in part diagram, like Fig. 1, but with a narrower space or field, through which a 10 textile cloth to be treated is drawn, between A. C. electrodes; and around cloth guide rollers, whereof the lower immersed guide-roller E'14, also constitutes an electrode; and with a revolving blade liquid stirrer 15 mounted on the roller, to agitate the liquid through the electric field and materials.

Fig. 4 is a vertical longitudinal section on line y' y' of Fig. 3.

Fig. 5 is a diagram of a rotary pole 20 changer or analogous device to change a direct current to alternating current, where only direct current is available.

Fig. 6 is a diagram of an induction coil 25 to change direct current to alternating current.

Fig. 7 is a perspective diagram of the guide roller and agitator and revolving electrode E'14 of Fig. 3.

Figs. 8 and 9 and 10 are wiring diagrams 30 in part, of circuits from alternating current source; with intermittent ground connections X in Figs. 8 and 10 only, Fig. 8 being for the apparatus of Figs. 1 and 2,—with ground connections X; and Fig. 10 for 35 the apparatus of Figs. 11 and 12; and showing by the directions of arrows between electrodes E E' the lines of opposing alternations or forces in and from opposing alternating electric fields between electrodes E and 40 E' constituting the terminals of different alternating current circuits in synchronism as regards frequency, and advantageously as regards voltage and amperage.

Figs. 11 and 12 are vertical sections of a 45 rotary or barrel-like type of apparatus for treating fibers in loose form or other than cloth, within a revolving reel with an alternating electric field between electrodes;—Fig. 11 being a vertical section on line y''' 50 y'''' of Fig. 12; and Fig. 12 a vertical section on line y''' y''' of Fig. 11.

Fig. 13 is a perspective view in diagram of three sets of alternating current rod-electrodes in two frames in lieu of plates for 55 any of aforesaid vessels—together with wiring diagram therefor.

In Fig. 1, a fibrous material, to wit a cloth S—S is shown, with further means not shown of moving same slowly or intermittently, flat or spread out, through a vat or vessel V, of wood or stoneware or other dielectric, at regulated speed, passing over and under loose guide rollers 3 and 4, through a dye-liquor or other suitable liquid 65 in the chamber 5 of the vessel V, under reg-

ulated temperature, controlled by cooling or heating coils 8 or their equivalent; E and E' being simultaneously both positive or both negative; and with means of repeatedly withdrawing and restoring, and circulating said liquor by well known means not shown, through said vat.

During such movement the cloth passes between two electrodes E and E' close together, each being of a different circuit constituting alternating terminal electrodes E and e, of one set, also E' and e' of another set, each set being the terminals of a different circuit advantageously differing in phase by about 180°, and with their respective 80 counterpart electrodes e and e' connected with the other and corresponding terminals of said circuits; both immersed in the liquor, and connected in multiple, or in series, through busbars 10 and 10' Fig. 2, and 85 others not shown, with the terminals of exteriorly generated alternating currents advantageously from a common source, of low frequency, from a symmetrical two-phase alternating current generator, advantageously with phase angle about 180 degrees apart; or from other A. C. sources with like phase differences but otherwise of same frequency and magnitude.

At H is shown a leader plate, like an electrode, but distant 95 therefrom and in contact with the liquor, and with intermittent earth connection X, details not shown, from the liquor through an interrupter, such as an electromagnetic polarized interrupter X in Fig. 8, in synchronism with the frequency of one of said alternating currents, advantageously making earth connection only with the positive alternation or only with the negative alternation of each cycle of one circuit, and with 100 impedance coils 55 in the other lead of the same circuit to balance the former. Such interrupter is advantageously cut out entirely where the opposing A. C. fields are applied.

Again, in order to attain two opposing A. C. differing in phase by about 180 degrees, I may also use a phase changing transformer as for instance to change a single phase 110 V. 60 cycles into two-phase, differing in phase by 180 degrees; 110 as for instance by using a single-phase transformer with two secondary coils, each of which will be connected in opposition to the other; substantially as illustrated by the two circuits 50 and 60 Fig. 8; or 50 and 56 115 Fig. 9; they would then be opposite in polarity, and consequently differ by about 180° in phase. And such transformer could also simultaneously be used to reduce or increase the voltage if desired in the customary 125 manner; i. e., reducing or increasing the relative number of turns in the secondary. And likewise transformers could be used to transform the ordinary three-phase into two-phase currents differing by about 180°. 130

Or in lieu of said polarized interrupter, I also use in series, in an insulated wire from said leader plate H,—a single electrolytic-rectifier cell or jar of well known type not shown, or equivalent device X to permit the passage of only positive charges to earth and holding back negative charges.

Between said interrupter or electrolytic cell and earth, I advantageously place in series, a Ruhmkorff induction coil, or a closed core transformer or the like,—the secondary from the latter being led to earth, and the lead from the interrupter or electrolytic cell constituting the primary thereof; thereby attaining a higher polarity force to cause discharge to earth.

The wires from said plate H and the interrupters are cut out entirely by due switching not shown, leaving the vat entirely insulated, in some cases, advantageously where the two opposing A. C. fields are applied; and such cutting out switch may be arranged to work automatically.

The vat has advantageously a false bottom, 6, perforated, beneath which is a space or receptacle for catching the deposit, if any, which may form with some dyes in working, before and during the dyeing, and which is to be frequently removed to prevent soiling the dye or material; such removal being effected either by pumping therefrom or from an exit pipe leading into a settling cistern (not shown) whence any sediment may be obtained to be utilized as may be practicable.

The vat is mounted on insulators, I, of glass or ebonite or the like, to insulate it from the floor or earth, care being taken to conduct the operation under insulated conditions. There may be several such vats in succession constituting a "range" of vats; or means of reversal may be provided so that the cloth may be run back and forth alternately until the treatment, *i. e.*, dyeing, is complete.

I prefer to attemperate the liquor to about 130 degrees F., such being advantageous for adsorption effects generally,—unless the dye materials require treatment at lower or higher temperature as empirically ascertained.

Figs. 3 and 4 are vertical cross-sections of another form of vat V, with very narrow alternating current field and chamber 5 for the liquor, and with length merely slightly in excess of the width of the textile S—S, which is shown as being drawn through the vat over the guide rollers 3—3 and under electrode roller E'14, between flat plate electrodes E e and E' e', like those of Fig. 1, being terminals of opposing different alternating current circuits, differing in phase by about 180°, and between roller electrode E' and E14, the terminals of two opposing and different alternating current circuits

differing in phase about 180°. Such narrow chambers have the material advantage of requiring a minimum amount of the liquor and a most efficient narrow alternating field between the electrodes in the liquid, which latter may be of comparatively poor conductivity, and hence require narrow fields or very greatly increased voltages. Such narrow vessels are also advantageous where induced A. C. fields only are to be used.

Fig. 7, shows, in diagram, a perspective of a combined revolving cylindrical electrode E' constituting also a guide roller as shown at 14 of vessel V, Figs. 3 and 4. Two of such placed parallel and close together may also be used in lieu of the ordinary "press rolls" or "tube rolls" or "drying cylinders" or calender rolls in this and like arts.

This roller electrode E'14 is advantageously made to project through but insulated from the sides of the vessel V mounted upon insulated bearings, 21 Fig. 7; or it may be suspended from the top of sides of vessel V, but with means of being revolved, as by a pulley around trunnion 17, or by the friction of the moving cloth.

Within the vessel, between the sides and the cylindrical electrode Fig. 7 E', and mounted around said trunnion 17 at one or each end, is a fly fan or blade wheel 16, advantageously of slightly less diameter than roller 14 which revolves with the roller and agitates and circulates the liquor in and through the vessel V.

The electrode E' of suitable material, such as aluminum or graphite or carbon, etc., is shown at 18 attached to the exterior of roller 14 with facilities for ready removal and replacing with same as desired.

Adequate insulated wires leading from the alternating current source through a busbar connect with the electrode E' Fig. 7 or 18 direct, or through suitable brushes resting upon an insulated collar not shown around trunnion 17, with a wire not shown from said collar to electrode.

In Fig. 3 such roller electrode E'14 is shown diagrammatically, and as a roller guiding the adsorbent, *i. e.*, the cloth S, between E' and its counterpart, the opposite alternating current electrode E15, of semi-circular form or having cross section of an arc of about $\frac{1}{3}$ to $\frac{1}{2}$ of circumference of the cylinder E' roller, and duly electrically connected with a like busbar or terminal not shown, of a second or opposing alternating current source, advantageously from same two-phase alternating current generator.

Through the axis of the trunnion 17 of the roller electrode there is provided a pipe 19, with exit at opposite end,—to carry into the roller, an attemperating cooling or heating liquid, advantageously in a coil, to cool the roller electrode when the heat from the

applied current becomes excessive, and which will cool or heat the surrounding liquor or adsorbent; or an additional exterior cooling or attemperating coil may be used.

In Figs. 11 and 12, vertical sections of the barrel or rotary type of dyeing machines for loose fibers or the like are shown, and the combination thereof with one form of 10 alternating current field between alternating current electrodes. The same is advantageously constructed of stoneware or pottery or a dielectric or of wood, vessel V containing the dye liquor, and with a revolving reel or cylinder of wood or other dielectric R, of 6 compartments, more or less to hold the loose fiber S; each compartment is adequately fitted with doors, and locks, and a means of circulation of liquor 15 which is forced or washed through holes bored through the exterior and perforated doors and partitions. The axle 17, on insulated bearings 21, carries revolving blades or fans 16 for agitating the liquor. Means, 20 advantageously from exterior, are provided for revolving the reel R; and for the admission, withdrawal and circulation of the liquor, and for the attemperating thereof; and I provide means of insulating the 25 supports of the apparatus, and for creating the alternating electric field within the vessel and reel during the treatment, in a manner analogous to that described for Figs. 1 and 3.

One method of creating the opposing 30 alternating electric fields in this barrel type, is illustrated, to wit, by means of curved plate terminal electrodes e and e' Fig. 11, surrounding part of the exterior of the revolving reel R, and not revolving therewith,—and the perforated plate corresponding electrodes E and E' Fig. 12 within the reel, advantageously along the radii in or partitions of each compartment, and revolving therewith; and which electrodes are 40 duly respectively independently connected with the circuits preferably from two-phase alternating current source, differing in phase by about 180 degrees, substantially as explained for Figs. 1 and 3. Such rotary 45 machines are also constructed on the principle of centrifugal machines and of hydro-extractors, with the addenda of the electrical field apparatus above explained.

In lieu of above electrodes E' of Fig. 12 50 or in addition thereto, the revolving electrode E' of Fig. 7 may advantageously be used to constitute the axle or shaft of the revolving barrel.

For cooling purposes the entire vessel V 60 may be set in tubs of circulating cold water or other cooling mixture; or the above described and usual attemperating coils may be used, in the liquid.

The same apparatus is used in the subsequent washing or boiling or both, of the

loose fiber and kindred articles, substituting potable water for the liquor—and advantageously simultaneously applying the alternating current fields.

In Fig. 2, are shown some details of the 70 plate electrodes E and E' removably attached to elbows 12, with insulated conductors 13, and electrically connected to busbars 10 and 10'; and with facilities for detaching electrodes E and E' from elbows 75 12 and 12' and replacing with electrodes of same or other material, or of different sizes. Several sets of independent pairs of electrodes can be connected with same busbars, if in same circuit. 80

Such busbars 10 will be used only where several pairs of electrodes are to be connected to the same alternating current source; where there is only one pair, such may be connected direct, without busbars 11. 85 Where two phase opposing circuits are used it will be understood that separate busbars as 10 and 10' for one circuit and 10'' and 10''' for the other circuit will be used.

The form and arrangement of the electrodes as shown in Figs. 1 and 2 may be altered but substantially of like area or surface, in some cases being rectangular and in others, circular plates—and in others annular or a ring plate surrounding a circular; 90 and again such may consist of a number of square or preferably round rods as in Fig. 13, or cylinders or tubes in lieu of wide flat plates arranged in suitable frames, as of wood or other insulator, and so as to permit 100 the removal or replacement of any thereof; such round rods give a maximum of surface per same weight of electrodes; and where hollow or tubular such may be arranged to carry a cooling liquid. 105

In the arrangement of the electrodes, it is advantageous to bring the like or positive electrodes as E and E' of two opposing circuits, as close together as practicable— 110 and yet permit the location between the electrodes of the cloth or fiber being treated, and with the simultaneous passing of the alternating currents, and simultaneous movement or passage or agitation of the liquid; or in other words, to so arrange the electrodes that the lines of force or flow of alternations or maximum amplitude or peak of the currents between one set of counterpart electrodes of one alternating circuit, shall be or approximately opposite and 115 nearly parallel to, or diagonal at very small acute angle to, and in simultaneous opposition to, the lines of force or flow of alternations, or of like maximum amplitude or peak of the currents between another set 120 of electrodes the terminals of another or opposing alternating electric circuit; such opposing lines of force meeting on the interposed fiber serving as an anvil. 125

It will be understood that the opposing 130

circuits may be from two separately generated alternating currents differing in phase about 180 degrees; or one thereof may be a shunt or branch circuit from the other 5 of equal voltage and amperage and frequency; and differing in phase about 180 degrees attained advantageously by placing in one lead of the shunt circuit a suitable capacity or condenser to cause the current 10 to lead about 90 degrees, and in the other lead an inductance and resistance to cause the current to lag about 90 degrees.

In Figs. 1 and 8, the sections of the electrodes show two sets, towit, E corresponding to the anode and e the cathode of one 15 set of like area, and E' the anode and e' the cathode of another set of electrodes of like area to each other and to the former set,—each set being connected with the terminals of a different circuit,—the former with circuit 60 and the latter with circuit 50 (Fig. 8), differing in phase about 180°. The terms anode and cathode are used merely for facility of describing the terminal 20 electrodes,—it being understood that with A. C. circuits, the anode becomes the cathode and vice versa with each change of alternation in each cycle. The anodes, *i. e.* terminals E and E' face and oppose each 25 other as do also the cathodes or terminals e and e'—with the fiber cloth practically constituting an anvil between E and e' on one side and E' and e on the other; and the anode terminals of one set adjoining, *i. e.* side by side with the cathode terminals of the other set.

The cathode plates e and e' are shown divided and placed on each side of our surrounding the anode plates E' and E respectively adjoining. Thereby I attain more acute angles between the lines of force or alternations from E to e with relation to the line of force from E' to e'—flowing simultaneously and in opposite directions—such 45 acute angles being considered as practically parallel for my said purpose.

In Fig. 13, I have shown, in lieu of plate electrodes, an advantageous form, towit; A number of narrow long round rod electrodes 50 assembled and held in two suitable wooden or other dielectric clamps or frames F and F', to be duly supported on the elbows 12 and 12' respectively of Fig. 2, connecting with the busbars 10 and 10' as in Fig. 2 for 55 one circuit, and 10'' and 10''' for the other circuit; and their upper or one end of the rods connected by a strip of lead or other suitable conductor; or they may be threaded into a bar of a suitable metal insulated and 60 electrically connected in parallel with the circuits 50 and 60 of Fig. 8, as indicated, through said busbars.

In frame F are shown in alternation, rod electrodes E', e, E', e, E', e; and in frame 65 F' are shown, in alternation, the rod elec-

trodes E—e—E—e—E—e; all the electrodes E—E' and E of frame F being connected with one line or terminal of circuit 70 60, and likewise all the counterpart electrodes e' of frame F with the other terminal 75 of circuit 60; and conversely the electrodes e—e—e of frame F are connected together and with the counterpart electrodes E—E—E of frame F' are electrically connected with the respective terminals of circuit 60 above 80 indicated; the currents in circuits 50 and 60 differing in phase about 180 degrees.

Thus the lines of force or alternations from E in frame F to e in frame F' are approximately nearly in opposition to lines 80 of force or alternations from E' in frame F to e' in frame F'; and likewise on reversal of currents. The cloth S—S is indicated as passing or placed between the frames F and F'. Details of the frame are not shown. It 85 is advantageous in the frames F and F' to have the distances between the rods of opposing sets of electrodes closer to each other than to the adjoining sets, *i. e.*, first e closer to first E' than to second E'. In some cases, 90 the said electrodes are tubular and lined with dielectric, and arranged to carry circulating cooling brines and the like.

The alternating electrode E and its counterpart e—also E' and its counterpart 95 e' are advantageously of equal area, and insoluble; and advantageously of platinum or lead or carbon, or graphite for acid and neutral solutions, and of iron in alkaline solutions. Other metals are also used depending upon the character of the solution,—and as to whether or not any such metal if in 100 solution or as a colloid, would be detrimental or advantageous; as for instance, silver electrode as affecting a silver solution 105 or dye, etc. The electrodes should be totally immersed or if not, the unimmersed portion should be protected with insoluble lacquer or varnish.

In my process, in all cases of doubt, as to 110 the electrodes in the alternating electrode classes of vessels which may injure the dye or other liquor, or the adsorbent, there should be used only the types of vessels utilizing induced alternating electric fields, 115 without electrodes.

It is also advantageous:

(1) to have the alternating current electrodes as close together as practicable depending upon the object to be attained, *i. e.* 120 whether the object is to dye a cloth or a yarn or the mere loose fiber; also (2) to increase the electrode surfaces as much as practicable, but of equal area, to enable the attaining of more amperage where such is desirable; with facilities of increasing or decreasing the area of the electrodes; and (3) to regulate the temperature of the liquor by means of the heat resulting from the electrodes or induced current;—and cooled 130

when necessary by means of a cooling coil or outer inclosing bath.

The electrodes are advantageously connected in multiple, though such may also be used connected in series.

In some cases the alternating electrodes and the immersed portions of wires leading thereto, are covered with a dielectric such as glass or glaze and the like; in which cases however much stronger currents of higher voltage must be used; and the alternating fields are like the induced electrostatic fields.

In the sundry wiring diagrams of the alternating current circuits shown in Figs. 8 and 9 and 10,

A. C. represents an alternating current generator; and being shown two-phase in Fig. 8 and single phase and a shunt therefrom in Figs. 9 and 10;

0 Lines 50 represent one circuit and lines 60 represent the other circuit differing in phase about 180 degrees; lines 50 leading to electrode E' and its counterpart e' of equal area; and 60 leading to electrode E and its counterpart e;

51 and 52 of Fig. 8 indicate the coils of one phase generator, and 61 and 62 the coils of the other phase, advantageously 180 degrees apart; N and S representing field magnets of alternating current generator.

H represents a so-called leader plate immersed in the liquid of the vessel, but insulated therefrom, and electrically connected to ground through X an interrupter, making 5 automatic connection for discharge to ground advantageously with each positive or negative alternation only, of each cycle of the A. C. in circuit 60. And 55 in series in the lead of circuit 60 represents an impedance coil to balance X.

I also utilize well known means (not shown) to attain and use in the circuits, A. C. of low or of medium or of high frequencies with suitable switches therefor; 5 and in all cases it is advantageous to switch out or dispense with all currents as from a polyphase generator or system, except the two A. C. differing in phase by about 180 degrees; and I further provide a switch to enable the use of one of the latter only; and another automatic switch to use a single A. C. field only for a few seconds followed by the two fields for a few minutes, or following a to and fro movement of the cloth.

15 In Figs. 8, 9, and 10, the arrow lines indicate the direction of alternations from electrode anode E to its counterpart electrode cathode e at any one instant; it will be understood that such alternations and directions are reversed with the alternation of each cycle of the alternating current; and the flow of arrows will point from e to E, or the reverse as drawn. The greater the distance of electrode E from electrode e, the

greater the voltage of the currents which must be used.

It will be understood that in placing the counterpart electrodes e and e' as shown in Figs. 1 and 8, in the liquid on opposite sides of the moving cloth S S, and as near as practicable to and side by side with E and E respectively, so as to attain simultaneously opposing or conflicting alternations, I thereby utilize both sets of electrodes similarly in succession, to attain hammer-like compacting alternations meeting approximately upon the interposed adsorbent, *i. e.* the fiber, and thereby driving out therefrom the free gases and hydrates and free soluble impurities and fixing or compacting with resulting increased density or specific gravity, the loose adsorbed compound on or in the fiber, or other interpolated or immersed adsorbent. In other words, where an adsorbent substance is immersed, and in some cases even 70 colloidal dissolved, such will take out of the suitable liquid by electric transference and adsorption, sundry selective oppositely charged colloids and particles, forming compounds which are "fixed" and with increased 80 density and stabilized under the influence of said conflicting electric stresses.

Though I use the terms "positive" and "negative," or anode and cathode, it will be understood, such is for facility of description 95 merely and that the positive becomes the negative pole or electrode with each change of alternation of each cycle of the alternating current.

Where only a single phase A. C. motor or 100 generator is available, as shown in Figs. 9 and 10, such current circuit 50 is divided into two phase currents differing in phase by about 180 degrees, the one division or A. C. circuit being connected with the like terminal electrodes E and e, and the other division or A. C. circuit, with the other or opposing sets of terminal electrodes E' and e'; there may be several of such sets, three being shown in diagram in the Fig. 9. 110

In such or analogous cases I advantageously attain the said two phase circuits as 56 and 57 Fig. 9, by placing in the shunt or branch 57 of one lead or wire, in series, a suitable capacity, C, *i. e.* condenser, to cause 115 the current to "lead" about 90 degrees; and I place in the other lead or wire, 57', in series, a suitable inductance *i. e.* an inductive coil, I, (choke-coil) and a non-inductive coil, R, (resistance) to cause the current to "lag" 120 about 90 degrees; such lead and lag together constituting the 180 degrees phase difference desired. It will be understood I do not restrict myself to said means of attaining such phase difference.

125 Though I may use a single phase symmetrical alternating current, with a shunt therefrom to constitute the opposing circuit, I

also advantageously use for my aforesaid purposes symmetrical alternating currents of a two-phase system advantageously differing in phase angle by 180 degrees; or two 5 independent symmetrical alternating currents, of like frequency, amplitude, voltage, and amperage and which two currents advantageously differ from one another in phase by about 180 degrees.

10 Where a polyphase generator or system only is available it is advantageous to cut out and avoid using in the liquid all currents except two, and such differing in phase about 180 degrees.

15 To generate such currents, I prefer to use a two-phase alternator or an alternating current generator giving symmetrical flat top waves of E. M. F.'s differing in phase angle by about 180 degrees, of same frequency 20 preferably 16, or I may use the commercial standard frequency 25, and with any voltage at point of generation, a transformer at point of user being utilized to give any desired voltage and amperage; and a frequency converter, etc., to attain desired frequency.

It will be understood that though I prefer an alternating field from symmetrical two-phase A. C. generator currents, yet I may 30 also use a direct current after changing it to alternating current; as for instance, through an induction coil, shown in diagram Fig. 6, using the alternating current from its secondary coil; or more advantageously by 35 transforming the direct into a low frequency alternating current by means of a suitable rotary converter or dynamotor, shown in diagram in Fig. 5.

And to attain equal opposing alternating 40 currents in the liquid, I may also use two such transformed and independent currents connected and arranged to flow through the liquids in circuits in opposition; or may use one such current with a shunt therefrom; 45 all as above explained for A. C. generator currents, and having a phase difference of about 180 degrees.

In some cases, especially where the source 50 of the alternating current is other than an alternator, *i. e.* where the secondary of a large induction coil as Fig. 6, is used as the source of alternating current and connected with one set of the electrodes, I also advantageously connect the secondary current 55 prior to the shunt, in parallel with a large condenser advantageously of glass; and where I use the induction coil type of transformer, Fig. 6, to change D. C. to A. C., I advantageously use therein a long vibrating 60 mechanical interrupter to attain low frequency in the secondary; and I construct the secondary coil more like the primary coil with merely such increase or decrease of turns to attain the desired increase or de-

crease of voltage, if any such increase or decrease be desired in the current circuit when applied in the liquid. And in all such cases where I use a shunt or branch circuit as from a single phase current or from the above secondary, to connect with the opposing electrodes, I place in one lead of the shunt or branch circuit, a suitable capacity or condenser to cause the current to lead about 90 degrees; and I place in the other corresponding lead a suitable inductance, advantageously, towit, an inductive coil, *i. e.* a choke coil and a non-inductive coil, *i. e.* resistance, to cause the current to lag about 90 degrees, and thereby I attain a phase difference of about 180 degrees in the opposing currents from the terminal electrodes. 65 70 75 80

In the art of dyeing textile fabrics, the latter are divided into two classes, towit (1) : fiber of animal origin, such as sheep wool, camel wool, silk, furs, feathers, hair, 85 etc. And (2) : fibers of vegetable origin such as cotton, linen, jute, ramie, straw, wood, paper, etc.

The basis of animal fiber is albuminoid matter, and such are more advantageously 90 treated as herein described than are the vegetable fibers.

The basis of vegetable fiber is cellulose matter.

The difference in each of the specifically 95 named fibers is in the proportion of said basis, albuminoid matter or cellulose matter respectively, to foreign or other substances contained within the fiber; hence there are dyes classified for different fibers 100 but many wool dyes are excellent for silk and other animal fibers and vice versa; and likewise with cotton and other vegetable fibers. In dyeing, the cellulose itself acts by mechanical adsorption, whereas the albuminoid acts by electrical adsorption; but the foreign substances contained within the cellulose fiber, or the mordants thereon, may be albuminoids other electrolytic or other substances, subject to electrical actions or 110 forces, and therefore in some cases the fibers of vegetable origin, like those of animal origin, may be subject to treatment by the electrical fields as herein described in addition to the mechanical adsorption effects 115 upon the cellulose.

Another classification in dyeing processes may be briefly described as follows:

First-class—Termed direct dyeing, when the color will dye the fiber direct in one 120 bath.

Second-class—Termed mordant dyeing or indirect dyeing, when the fibers or goods must be treated with a mordant before or after they have been dyed. The coloring 125 effect does not come from the dyestuff alone, but from the combination of a mordant that is saturated first on the fiber and combines

with the coloring matter from the dye bath later.

The colors that dye direct (first class) can be divided into two groups, to wit: for vegetable or animal fibers:

1st (a) Substantive colors which when properly dissolved in hot distilled water, and added to the coloring bath containing either a small per cent. of common salt or 10 Glauber salt will dye fast, the cotton and other vegetable fibers.

1st (b) Acid colors which when thus dissolved with a little sulfuric acid or sodium bisulfate will dye fast, wool or other animal fiber. While the direct colors are fairly fast, the mordant dyeing is more fast in the majority of cases.

Again in vat dyeing, the coloring stuff itself is insoluble in water. Since water is 20 the vehicle which carries the dyestuff upon the fiber, the following technic is ordinarily used, illustrated by one vat color, to wit indigo. Indigo color is insoluble in water, but when indigo is mixed and dispersed in 25 a water solution of or with a hydrosulfite salt, the indigo is reduced to a new compound and becomes soluble in water. This solution is either clear as water or yellowish. The fibers or goods to be dyed are worked 30 in this solution and my A. C. field, herein described; then taken out and washed and hung up, advantageously in my A. C. field under insulated conditions so that every 35 part of the fiber is in contact with the air advantageously blown thereon, and through the vessel while the A. C. field is simultaneously acting thereon, under insulated conditions, the reduced compound of indigo which is now on the fiber and is electro-negative and is not colored at first, yet when 40 thus brought in contact with the air, is oxydized and as fast as it is oxydized, the blue color appears upon the textile.

In the carrying out of the process of the 45 present invention in the apparatus described, as illustrated in dyeing of fibers including the so-called after-treatments, the absorbent *i. e.* the fibrous material, cloth and the like, is introduced and moved through 50 the vessel V of Fig. 1 or Fig. 3; and between the opposing electrodes E and E', or e and e' or both; or if the form be not a cloth, the loose fiber or fibrous material of 55 sundry forms, is introduced into, and agitated in the barrel of vessel V of Fig. 12; and the dye liquor is introduced into and agitated in and moved through, said vessels and in and around and through said adsorbent in said vessels; care being taken that 60 the fiber is kept submerged, etc. as in present dyeing methods; but with the addition of the simultaneous application during such movement, of the single A. C. field with a direct current superimposed of about 1½% 65 of the strength of the A. C. under insulated

conditions; and to be duly maintained in said liquids and fibers for a few minutes generally while the material is moved therethrough or to and fro therein, until the desired effect *i. e.* the dyeing has been accomplished,—and with due provisions for renewing the dye bath when exhausted,—and for regulating the temperature thereof by means of the alternating current or of heating coils or cooling coils; and varying in 70 different cases. Other details of operation have been set forth in describing the different types of apparatus.

Alternatively in some cases I first pass the cloth through the vat applying only a single 80 A. C. field of low frequency; and thereafter again pass the cloth through the same vat while applying the two opposing fields, preferably differing in phase by about 180 degrees, allowing longer time for the latter 85 passage than the former or repeating the latter passage several times.

It is important to conduct the process under insulated conditions,—and including thereunder not only complete insulation, as 90 heretofore commonly understood, but also partial insulation, intermittently, especially where only the single A. C. field is applied and as regards only negative or only positive charges or alterations, or current;— 95 that is to say, a state of insulation which yet permits intermittently to pass to earth and the like, only the surplus or free positive or only the negative charges or current alternations in synchronism with the frequency 100 of the A. C. and simultaneously and automatically insulating or withholding in the liquid, the correlative negative or positive charges only.

And such is especially important with explosive systems or products as are some dye-stuffs including these specifically named herein but also others of like nature whether liquid or gaseous or solid or dust-like, etc. In conducting the process with any explosive 110 dye substances, I advantageously maintain the insulation so as to permit surplus free negative charges only to pass to earth, etc., and avoid sudden or any withdrawal of positive charges and seek to accumulate 115 positive charges upon the dispersoids or other particles of the products, and thereby attain substantial stability therein, as also other advantages herein recited.

Adsorption is an instantaneous operation, 120 and to attain such I advantageously use a single A. C. of low frequency with an interrupter in a ground line as described, but following such and to attain the "compacting" of the compounds, as described by the 125 alternations or stresses of two opposing or conflicting equal A. C. of like frequency and without earthing. The latter currents are often advantageously A. C. of medium or of high frequency,—such latter currents being 130

- duly provided and "switched" into the circuits after about a few minutes application or use of the low frequency currents covering an estimated period for diffusion in addition to adsorption though the low frequency current only be used in many cases,— to be determined empirically. But where the adsorption colloids or compounds are to be retained in solution or in disperse state 10 as in the dye liquor then it is advantageous to follow the instantaneous application of the low frequency A. C., by a more prolonged application of medium to high frequency A. C.
- 15 By low frequency I mean not over 60 cycles, and advantageously 16 cycles to 25 cycles. By medium frequency, I mean about 100 to 1500 cycles. By high frequency, I mean any above latter and up to that used 20 in wireless telegraphy.

To attain the former, I advantageously use the frequency converter or dynamotor. And to attain the medium frequency I may use the spark coil or the secondary current from 25 an induction coil or the like, and for high frequency, I use other suitable means, as used in wireless telegraphy.

When the adsorptions have been practically attained, in the A. C. fields of low frequency, during which use the colloids and dispersoids have taken up a positive or a negative charge, and a correlative amount of surplus free negative or positive charge respectively, has been taken up by the leader 30 plate (H) and thence through the interrupter or discharge valve "X" to earth etc.;—then thereafter the latter is not required or advantageous, during the "compacting" operation, when the opposing A. C. fields of low medium or high frequency are applied as described. The interrupter is 35 then "cut out".

I advantageously use an A. C. voltage to attain in the liquid a voltage of about one 40 and one-half up to 30 volts where there is ample natural dissociation of molecules into ions due to mere solution in the liquid; otherwise a voltage up to about 440 volts in the liquid is desirable, though often that of 45 ordinary light currents, 110 to 220 volts, is ample. Where a single A. C. only is used, it is advantageous to superimpose a direct current in the liquid of about 1½% of the voltage of the A. C.

50 The treatment may be intermittent, the cloth being moved back and forth, and the liquor being alternately discharged and renewed or reinvigorated with fresh supply; or the process may be continuous, by duly 55 regulating the inflow and outflow of liquor and of the replacement of new or continuously passing cloth etc. The flow of liquor can be effected by force pump or injector or by suction or gravity, or same can be agitated by revolving blades as shown, *i. e.*:

if sufficient agitation be not attained by or from the alternating current effects.

During the passage or agitation or movement of the liquid and the fiber coil etc. between the electrodes, or of the liquid through 70 the fibrous mass while the current is passing, the effects above described are attained, *i. e.* the dyeing and the product thereof.

After such treatment, the liquor can be drawn off through withdrawal pipes at bottom of vessels; and the fiber is washed or well wrung and rinsed or otherwise treated as at present, either in the same vessels and advantageously with the electric treatment as aforesaid, but with fresh potable water, 75 or other suitable liquid, or otherwise as per "the after-treatments" now ordinarily pursued in the finishing of dyed materials and which I call "suitable after-treatments".

In the after-treatment of silk especially 80 in cloth form, as by passing the silk through a very dilute solution of acetic or tartaric acid, advantageously tartaric, I practise my process also in such after-treatment by passing same through the single and opposing 85 alternating current fields in aforesaid apparatus, and thereby the silk fibers adsorb the dye and retain same mostly fixedly; and is then dried without washing, advantageously in a suitable chamber heated by air and with 90 two opposing fields of high voltage and amperage; and thereby its luster is enhanced; and the silk thereby acquires the property of emitting a crackling sound when twisted or 95 "rustled".

I also use my process substantially as described between A. C. electrodes in the dye-liquor and following with like passages through an induced A. C. field, advantageously, in the oxidation step of dyeing in the 100 fiber, as of aniline black—especially in what is known as the "aging" process where the oxidation is not accomplished in the dye liquor itself, but the fabric is removed from it, dried and then "aged",—that is, subjected 110 in a suitable chamber or vessel to a warm moist atmosphere which develops the black; and in which chamber I apply my opposing induced A. C. fields advantageously in a vessel like Fig. 3 covering the electrodes 115 with dielectric material.

The aging chamber is generally fitted with a powerful fan at the top which draws in air and steam from the bottom; ample heat to attain the desired temperature, advantageously 35 to 45 degrees C., is furnished by the alternating current insulated electrodes, or induction apparatus; otherwise by means of suitable attemperating coils.

120 My process is also applicable and advantageous in what is known as dyeing "on the fiber". A typical instance in "paranitranilin red", a synthetic dye; to produce this dye, the material to be dyed is impregnated 125 130

with B-naphthol by passing through a first bath, an alkaline bath of this compound, and is then passed into a second bath containing diazotized paranitranilin,—the dye 5 thus being produced on the material; in both baths, or advantageously in latter only, I use my aforesaid process by applying the single followed by the opposing alternating current fields.

10 The loose or interlaced threads or masses of other fibers, or cloth, or paper and the like therefrom, which I classify as adsorbents and which may be similarly treated as herein described, are silk, wool, cotton, 15 linen, (flax) "fibrin flocks", paper hemp, jute, the so-called jelly-fibers, asbestos, slag-wool, and the like.

I do not restrict my said process to textile cloth or fiber; I also apply the same 20 to what are known as imitation textiles; to artificial filaments and manufactures therefrom; and to artificial or "imitation leathers" and leather coating, and in tanning and enameling; and to imitation furs; to artificial feathers; to india-rubber substitutes; to waterproofing compositions; to enameled paper; to paper making generally; to intensive treatment of paper; to wall coverings; to celluloid and the pyroxylin plastics, and 30 manufactures therefrom.

I also apply the same process in sundry substances including industries where fibers constitute a base to adsorb sundry adsorbable compounds or dispersoids or colloids 35 from a suitable solution or liquid; as for instance, insulating compound, using cellulose as a base; also in the making of cellulose acetates; also as in making cellulite films for kinematographs; also in color printing; 40 also in making artificial silk; and photographic papers; insulating compounds using fibers as a base; in sizing of fibrous material; and the like; also in making sundry intermediates directly required for dyeing 45 or making dyestuffs.

The process and apparatus is also applicable in sundry manufacturing of india rubber, other than molded goods; also of synthetic rubber; such as in the making of rubber "shoddy" sheeting or fabric; and in the rubber "spreading" or making of proofed textiles; and in rubber dipped goods such as gloves, and other thin articles. And especially so in the present operation of "calendering" and "frictioning".

I claim;

1. A process of electric treatment in the dyeing of fibers and fibrous materials, with suitable dyestuffs, which comprises dissolving, and dispersing dyestuffs in suitable liquid mobile media, and blending and mixing the solutions and then immersing therein and passing therethrough the fibers and fibrous material, in an alternating current field from an A. C. source of regulated fre-

quency voltage and amperage under suitable temperature and speed and time period, and under insulated conditions.

2. A process of electric treatment in the dyeing of fibers and fibrous material with 70 suitable dyestuffs, which comprises dissolving, and dispersing the dyestuff in suitable liquid mobile media, and passing the fibers and fibrous material through the solutions in an alternating current field from an A. C. 75 source of regulated frequency voltage and amperage and under suitable temperature and speed and time period, and under insulated conditions, and with intermittent ground electrical connection from the solutions through an interrupter passing only 80 unbalanced charges of one kind therefrom to earth.

3. A process of electric treatment in the dyeing of fibers and fibrous material, which 85 comprises dissolving, and dispersing dyestuff compounds in suitable liquid mobile media, and bringing the fibers and fibrous material in contact with the solutions in an alternating field from an A. C. source of regulated 90 frequency voltage and amperage under suitable temperature and speed and time period, and under insulated conditions; and with intermittent ground electrical connection from the liquids passing, only free unbal- 95 anced positive charges to earth, in synchronism with the frequency of the A. C. creating said field.

4. A process of electric treatment in the dyeing of fibers and fibrous material which 100 comprises dissolving, and dispersing the dye- 105 stuff compounds in a mobile medium in an alternating current field from an A. C. source of regulated frequency and strength and under suitable temperature and speed and time period, and under insulated conditions; and with intermittent ground connections from the mobile medium passing only free unbalanced negative charges to 110 earth, in synchronism with the frequency of an A. C. creating said field.

5. The process of electrically treating fibers and fibrous material in the dyeing thereof, which comprises subjecting the same, under insulated conditions, in a suitable liquid dyestuff solution, to simultaneous opposing alternations and stresses, from the alternations of opposing alternating current fields, created by alternating currents of regulated frequency and strength, arranged 115 to flow in opposing circuits in the liquid, the liquid being connected to earth through an interrupter making earth connection in synchronism with the one kind of alternation of each cycle of one of the alternating currents in one lead of one circuit, and balanced by an impedance coil in the other lead of said circuit.

6. The process of electrically treating fibers and fibrous materials in the dyeing 125 130

- thereof which comprises subjecting the same while immersed in suitable dyestuff solutions under insulated conditions to the influence of the alternating stresses in alternating electric fields from alternating currents of same frequency and strength arranged to flow in opposing circuits in said solutions, the liquid being connected to earth through an interrupter making earth connection with the positive alternation of each cycle of one of the alternating currents in one lead of one circuit and balanced by an impedance coil, in the other lead of same circuit.
7. The process of electrically treating fibers and fibrous materials in the dyeing thereof, which comprises subjecting the fibers, while in motion in a suitable liquid dyestuff solution, under insulated conditions, to the influence of the alternating stresses in alternating electric fields, created simultaneously in the solution by alternating currents from a polyphase generator, with regulated frequency and strength, and with circuits leading therefrom to and through the liquid arranged so that the positive E. M. F. and alternations of one circuit meet in the liquid the opposing E. M. F. and alternations of the other circuits of the polyphase system.
8. The process of treating fibers and fibrous materials in the dyeing thereof, which comprises subjecting the same, under insulated conditions to the influence of opposing alternations and stresses of alternating current fields from A. C. of regulable frequency and strength, in a suitable liquid dyestuff solution previously duly changed to an acid state.
9. The process of treating fibers and fibrous materials in the dyeing thereof which comprises subjecting the same, under insulated conditions to the influence of conflicting alternations, and stresses from alternating current fields from A. C. of regulated frequency and strength, in a suitable liquid dyestuff solution previously duly changed to an alkaline state.
10. The process of treating fibers and fibrous materials, in the dyeing thereof, which comprises subjecting the same, under insulated conditions to the influence of conflicting alternations and stresses from alternating current fields from A. C. of regulated frequency and strength in a suitable liquid dyestuff solution previously duly changed to a neutral state.
11. The process of treating fibers and fibrous materials in the dyeing thereof, which comprises subjecting the same, under insulated conditions, to the influence of opposing alternations and stresses from alternating current fields from A. C. of regulated frequency and strength, in a suitable liquid dyestuff solution previously duly changed to an acid state; and thereafter repeating the electrical treatment in a liquid dyestuff solution previously changed to an alkaline state.
12. As a new article of manufacture, a dyed fabric, comprising dyestuffs electrically adsorbed and compacted thereon.
13. As a new product, a dyed fiber or fibrous material having therein and thereon electrically adsorbed, fixed and compacted sundry adsorbable dyestuff dispersoids and suspensoid colloids from dyestuffs and being substantially free from amphoteric emulsoids and reversible compounds from dyestuffs.
14. As a new product, a stable dyed fiber or fibrous material containing electrically adsorbed and compacted suspensoid dyestuffs and chemical compounds of dyestuffs and being substantially free from amphoteric emulsoid dyes and reversible colloidal dyestuffs.
15. A dyed textile fiber and the like comprising irreversible non-amphoteric colloidal dyes electrically adsorbed and compacted upon the fiber and freed from reversible emulsoid colloid dyes.
16. A dyed textile fiber and the like, having dyes of electrically enhanced true density and comprising irreversible non-amphoteric colloidal dyes electrically adsorbed and compacted upon the fiber, and freed from reversible emulsoid colloidal dyes, and water-soluble ingredients.
17. As a new manufacture a dyestuff soluble adsorption compound having stable fixed molecular structure with electrically adsorbed suspensoid colloids and particles in non-strained equilibrium and free from electrically amphoteric colloids and particles.
18. As a new manufacture, a soluble dyestuff having stable molecular structure with electrically adsorbed suspensoid colloids and particles in non-strained equilibrium.
19. As a new manufacture, a fibrous material dyed with a dye having stable molecular structure with electrically adsorbed suspensoid colloids and particles from dyestuffs in non-strained equilibrium.
20. An apparatus of the nature described, comprising a vessel having an insulated chamber holding a suitable dyestuff liquid, means for attemperating the liquid, means for immersing and agitating therein a mass of fiber and fibrous material, means for supplying thereto and removing therefrom and agitating therein a suitable liquid dyestuff and means for maintaining therein alternating current fields from A. C. source of regulable frequency and strength under insulated conditions.
21. An apparatus of the nature described, comprising an insulated vessel having a chamber holding a suitable dyestuff liquid, means for attemperating the liquid, means

for immersing and agitating therein a mass of fiber and fibrous material, and means for maintaining in said liquid dyestuff alternating current fields from A. C. source of 5 regulable frequency and strength, in opposing circuits between terminal electrodes, under insulated conditions.

22. An apparatus of the nature described, comprising an insulated vessel with means 10 for supplying and withdrawing therefrom and repeatedly circulating therein a suitable dyestuff liquid, means for attemperating the liquid, means for passing therethrough, at regulated speed, a fibrous material, and 15 means for maintaining in said liquid alternating current fields from A. C. sources of regulable frequency and strength in conflicting circuits from a polyphase generator, under insulated conditions.

23. An apparatus of the nature described, comprising an insulated vessel in combination with insulated means for supplying and withdrawing therefrom and moving agitating and circulating therein, a suitable dye- 20 stuff liquid at regulated temperature; insulated means for passing therethrough, at regulated speed, a fibrous material in contact with said suitable liquid; insulated means for providing and maintaining in said liquid 25 in said vessel conflicting alternating currents and stresses from A. C. sources of regulable frequency and strength under insulated conditions; insulated means for electrically connecting the said liquid in said 30 vessel to earth, through an interrupter making and breaking earth connections with the positive alternation of each cycle of one lead of one of the alternating current circuits, and balanced in the other lead of same alternating 35 current circuit by a suitable impedance coil; means for electrically connecting the insulated vessel and insulated apparatus to earth through an insulated electrolytic-rectifier cell permitting positive charges only to 40 pass to earth; means for placing an insulated inductive resistance in series in each of said A. C. circuits.

24. In apparatus of the nature described, comprising an insulated vessel, in combination 45 with insulated means for supplying and withdrawing therefrom and moving, agitating and circulating therein, a suitable dye-stuff liquid at regulated temperature; insulated means for passing therethrough at 50 regulated speed a fibrous material in contact with said liquid; insulated means for providing and maintaining in said liquid in said vessel, approximately opposing alternating stresses and currents with means of 55 control as to voltage, frequency and amperage of currents in said liquid; insulated means for electrically connecting the said liquid in said vessel to earth, through an 60 interrupter making and breaking earth connection with the negative alternation of each

cycle of one lead of one of the alternating current circuits, and balanced in the other lead of same alternating current circuit by a suitable impedance coil; means for placing an insulated inductive resistance in series in 70 each of said A. C. circuits; and with means for placing an insulated condenser in each A. C. circuit.

25. An apparatus of the nature described, comprising an insulated electric vessel, in 75 combination with insulated means to move therethrough a fibrous cloth material and having therein a suitable dyestuff solution for dyeing same, under insulated conditions; several sets of electrodes immersed in said 80 solution, each set being the terminals of separate alternating current circuits, the anode of one set being placed opposite to the anode of another set of electrodes, and with the cathode of such latter adjoining and insulated from the anode of the former and vice versa; insulated means of placing and moving between the said opposite electrodes, the fibrous cloth material immersed in the solution; with means for agitating the 85 liquid; insulated means of generating and connecting with said sets of electrodes, the circuits of alternating currents from a polyphase generator and the circuits therefrom flowing in approximate opposition when in 90 said liquid, with means of control as to frequency voltage and amperage of said currents in said liquid; and with earth connection from said liquid through an interrupter and a Ruhmkorf coil beyond the 95 interrupter and making earth connections with one and the like alternation of each cycle of the alternating current of one of said circuits and with balancing impedance coils in the other lead of said circuit; means for 100 electrically connecting the insulated vessel and apparatus to earth through an insulated electrolytic rectifier cell permitting positive charges only to 105 pass to earth.

26. In an apparatus of the nature described, a vat holding a dispersed dyestuff in liquid medium, means for insulating and attemperating same with its contents, means for agitating a suitable dyestuff liquid in contact with a fibrous material therein, and 110 means for producing therein approximately opposing alternating electric stresses from A. C. sources of regulable frequency and strength, under insulated conditions.

27. In an apparatus of the nature described, a receptacle for treating fibrous material with suitable dyestuff liquids, means for insulating and attemperating and moving to and fro the fibrous material therein, means for providing in such receptacle and 115 in the liquid therein approximately opposing alternating current stresses from A. C. sources of regulable frequency and strength under insulated conditions.

28. In an apparatus of the nature de- 120

scribed, a receptacle for treating fibrous material with suitable dyestuff liquids, means for insulating and attemperating and circulating the fibrous material and liquids therein, means for providing in the liquid therein approximately opposing alternating current stresses from A. C. sources of regulable frequency and strength under insulated conditions, and means for earth connection 5 from the liquid through an interrupter, making earth connection with one kind of alternation of each cycle of one alternating current.

29. In an apparatus of the nature described a set of two revolving insulated roller electrodes having exterior surface plate electrodes constituting terminals of two independent A. C. circuits, the anode of one alternating current circuit opposite 15 and parallel to a like anode of another alternating current circuit, with means for 20

changing and adjusting the distance between the rollers, with means for passing fibrous material between the said opposing electrodes of different sets of electrodes immersed in a suitable dyestuff liquid, under insulated condition, with means for revolving the roller electrodes. 25

30. A dyestuff comprising electro-negative dyestuff components and adsorption 30 compounds of enhanced stability.

31. A fiber dyed with a dyestuff comprising electro-negative adsorption components and compounds of enhanced stability and having dyestuff elements electrically fixed. 35

Signed at Newark in the county of Essex and State of New Jersey this 16 day of November, A. D. 1917.
